(57) **CLAIM**

The ornamental design for a myofascial release tool, as shown and described.

DESCRIPTION

FIG. 1 is a front perspective view of the myofascial release tool showing my new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The broken lines shown in the Figures depict portions of the article that form no part of the claimed design.

1 Claim, 4 Drawing Sheets(56)
